UNITED STATES PATENT OFFICE

167,096

PRESSING IRON

Frederick W. Perl, Mansfield, Ohio, assignor to
Westinghouse Electric Corporation, a corpora-
tion of Pennsylvania

Application February 18, 1952, Serial No. 18,562

Term of patent 14 years

(Cl. D49—6)

To all whom it may concern:

Be it known that I, Frederick W. Perl, a citizen of the United States, residing at Mansfield, in the county of Richland and State of Ohio, have invented a new, original, and ornamental Design for a Pressing Iron, of which the following is a specification, reference being had to the accompanying drawings forming a part thereof.

Figure 1 is a front perspective view of a pressing iron incorporating my new design;

Figure 2 is a side elevational view thereof;

Figure 3 is a plan view thereof; and

Figure 4 is a plan view thereof similar to that shown in Figure 3 but having the handle cut away to show more clearly details of the design.

The dominant features of the design reside in the portions shown in full lines.

I claim:

The ornamental design for a pressing iron, sub-
stantially as shown and described.

FREDERICK W. PERL.
